US00D839597S

(12) **United States Design Patent** (10) Patent No.: **US D839,597 S**
 Courtney et al. (45) Date of Patent: ** *Feb. 5, 2019

(54) DENTAL CLEANING APPLIANCE	1,847,495 A	3/1932	Priest
(71) Applicant: Dyson Technology Limited , Wiltshire (GB)	1,959,601 A	5/1934	Schulze
(72) Inventors: Stephen Benjamin Courtney , Bath (GB); Timothy Nicholas Stickney , Gloucester (GB); Jonathan George Marsh , Swindon (GB); Adam James Bates , Oxford (GB); Peter David Gammack , Gloucester (GB)	2,036,706 A	4/1936	Law
	D113,432 S	2/1939	Newman
	2,318,460 A	5/1943	Brief
	D153,130 S	3/1949	Fischer
	2,490,185 A	12/1949	Work
	D197,763 S	3/1964	Aymar
	3,370,415 A	2/1968	McIlvaine
	3,728,035 A	4/1973	Reitknecht
	3,734,106 A	5/1973	Zimmerman
	D230,654 S	3/1974	Fishbein
	D258,237 S	2/1981	Anspach
	4,277,194 A	7/1981	Smith
	D264,359 S	5/1982	Grubb et al.
(73) Assignee: Dyson Technology Limited , Malmesbury, Wiltshire (GB)	4,344,184 A *	8/1982	Edwards H04B 1/04 343/702
(*) Notice: This patent is subject to a terminal disclaimer.	D276,935 S	12/1984	Fattaleh

(57) **CLAIM**

We claim the ornamental design for a dental cleaning appliance, as shown and described.

DESCRIPTION

FIG. 1 is a perspective view of a dental cleaning appliance showing our new design;

FIG. 2 is a front view thereof;

FIG. 3 is a rear view thereof;

FIG. 4 is a side view thereof;

FIG. 5 is a side view of the opposite side of FIG. 4;

FIG. 6 is a top view thereof; and,

FIG. 7 is a bottom view thereof.

The broken lines shown in the drawings illustrate portions of a dental cleaning appliance that form no part of the claimed design.
